US0D1105210S

(12) **United States Design Patent** (10) **Patent No.:** **US D1,105,210 S**
(45) **Date of Patent:** **** Dec. 9, 2025**

(54) **LIGHTING EQUIPMENT FOR AUTHENTICATION**

(71) Applicant: **NEC Corporation**, Tokyo (JP)

(72) Inventors: **Masahiko Osaka**, Tokyo (JP); **Tomomasa Sano**, Tokyo (JP); **Hinano Tanaka**, Tokyo (JP); **Satoshi Shikata**, Tokyo (JP); **Aozora Hamano**, Tokyo (JP)

(73) Assignee: **NEC Corporation**, Tokyo (JP)

(**) Term: **15 Years**

(21) Appl. No.: **29/827,146**

(22) Filed: **Feb. 17, 2022**

(30) **Foreign Application Priority Data**

Aug. 20, 2021 (JP) ..... 2021-017958 D

CLAIM

The ornamental design for a lighting equipment for authentication as shown and described.

DESCRIPTION

FIG. 1 is a front, right side, top perspective view of a lighting equipment for authentication showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The portions depicted by broken lines are for illustrative purpose only and form no part of the claimed design.

1 Claim, 7 Drawing Sheets
